Patented Apr. 25, 1916.

UNITED STATES PATENT OFFICE.

ARCHIE RAYMOND URIE AND FREDERICK PHILIP UHRIG, OF LA CENTER,
WASHINGTON.

BOILER-FLUE CLEANER.

1,180,960.

Specification of Letters Patent. Patented Apr. 25, 1916.

Application filed May 13, 1915. Serial No. 27,848.

To all whom it may concern:

Be it known that we, ARCHIE RAYMOND URIE and FREDERICK PHILIP UHRIG, both citizens of the United States, and residents 5 of La Center, in the county of Clarke and State of Washington, have invented a new and Improved Boiler-Flue Cleaner, of which the following is a full, clear, and exact description.

0 The object of the invention is to provide a new and improved boiler flue cleaner which is simple and durable in construction, easily manipulated and arranged to insure complete removal of accumulated scale from a 5 flue by injecting a mixture of steam, sand and air into the flue to be cleaned.

In order to accomplish the desired result use is made of an apparatus for forcing a mixture of steam, air and sand through a 20 flue to clean the same, the apparatus including a steam injector connected with a source of steam supply and a sand and air suction device connected with the said injector and with a sand supply and with the atmosphere 25 to cause sand and air to be drawn by the action of the steam into the said injector to be forced by the steam into and through the flue or pipe to be cleaned.

A practical embodiment of the invention 30 is represented in the accompanying drawings forming a part of this specification, in which similar characters of reference indicate corresponding parts in all the views.

Figure 1 is a perspective view of the boiler 35 flue cleaner as applied; Fig. 2 is an enlarged sectional side elevation of the boiler flue cleaner; Fig. 3 is a transverse section of the same on the line 3—3 of Fig. 2; Fig. 4 is a sectional plan view of the sand and air suction device, the section being on the line 4—4 of Fig. 2; and Fig. 5 is a side elevation of 40 part of the boiler flue cleaner provided with a discharge pipe having an upward bend for cleaning vertical flues.

45 The casing A of an injector is provided with a chamber B having a forwardly extending outlet C leading into a pipe D screwed or otherwise attached to the forward end of the casing A. The terminal of 50 the pipe D is adapted to pass into the flue or pipe E to be cleaned, as plainly indicated in Fig. 1. The chamber B is provided with an inlet F, preferably located at the bottom, and to the inlet F is coupled a coupling G held at one end of a hose or flexible tube H

connected with a steam boiler or other suitable source of fluid pressure supply. A nozzle I extends centrally through the back of the casing A and through the chamber B into the outlet C, the terminal of the nozzle I being concentric with the outlet C. The outer end of the nozzle I is preferably bent downward and is provided with a short pipe J to which is coupled a coupling K held on one end of a hose or a flexible tube L connected at its other end by a coupling K' with the outlet N' of a sand and air suction device N.

The sand and suction device N is preferably made in the form of a pipe bent into U 70 shape to provide the outlet N', the air inlet N² and a bend N³, the bottom N⁴ of which is adapted to rest on the bottom of a pail O filled with sand or other similar material P. The bend N³ is provided at one or both sides 75 with a slot N⁵ through which the sand P in the pail O can pass into the suction device N at the bend N³. The air inlet N² is provided with a valve Q under the control of the operator for regulating the amount of 80 air passing into the air inlet N². As shown, the valve Q is in the form of a sleeve fitting exteriorly on the air inlet N² and closed at its upper end, and the valve Q is provided at 85 its side with an opening Q' adapted to register more or less with an opening N⁶ formed in the wall of the air inlet N². The top of the base N⁴ is preferably flat and is flush with the bottom of the sand inlet N⁵ to allow the sand to pass readily over the top of 90 the base N⁴ into and through the sand inlet N⁵. The outlet N' is slightly contracted from the bottom upward to insure a proper flow of the sand and air when the boiler flue cleaner is in use. The back of the nozzle I 95 is provided with a suitable handle R adapted to be taken hold of by the operator for conveniently manipulating the boiler flue cleaner. For cleaning vertical flues the pipe D is provided with an upward bend D', as 100 shown in Fig. 5.

The operation is as follows: When the several parts are in the position shown in the drawings and steam or other fluid pressure is allowed to flow through the hose H into 105 the chamber B and through the outlet C then a suction is produced in the nozzle I and the suction device N to cause the sand P to pass from the pail O through the opening N⁶ into the bend N³ and to cause air to 110

pass through the registering openings Q' and N⁶ into the air inlet N². The suction produced causes the sand and air to pass through the outlet N' into the hose L and 5 by way of the pipe J into the nozzle I and out of the same into the outlet C to mix therein with the steam or other fluid, which latter by its impelling force forces the mixture through the pipe D into the flue E to 10 be cleaned. It will be noticed that the steam in the mixture tends to soften the scale which has accumulated in the flue or pipe E and the sand blast readily dislodges the scale so that the latter is quickly dislodged and 15 forced out of the flue or pipe E. It will further be noticed that by the operator having hold of the handle R the pipe D can be readily placed into the end of any one of the flues or tubes E to be cleaned and it takes 20 but a comparatively short time to effectively clean the flue or pipe of the accumulated scale.

It is understood that the sand P in the pail O is comparatively dry to enable the 25 air entering the inlet N² to carry the sand along and to allow the sand to readily flow from the pail through the opening N⁵ into the bend N³ to be taken along by the air.

The boiler flue cleaner shown and described is very simple and durable in construction and composed of very few parts not liable to get out of order, and it does not require the employment of skilled labor for manipulating the boiler flue cleaner.

Having thus described our invention, we claim as new and desire to secure by Letters Patent:

1. A boiler flue cleaner, comprising an injector having an annular chamber provided 40 with a steam inlet and with an outlet at right angles thereto, the inlet being adapted to connect with a steam supply, a discharge pipe connected with the said outlet and adapted to engage the flue to be cleaned, a 45 nozzle extending centrally through the said

chamber and having its terminal concentric within the said outlet, a sand and air suction device in the form of an upstanding U-shaped pipe having a sand inlet at the bend and a valved air inlet at one upper end, and 51 a flexible connection between the said nozzle and the other end of the said U-shaped pipe.

2. A boiler flue cleaner provided with a sand and air suction device of approximately U-shape forming upstanding side members 55 connected with each other at their lower ends by a bend, the latter having an elongated sand inlet extending partly across each member, one of the said members having an air inlet adjacent its upper end and 60 a sleeve valve controlling the same, and the other side member having a contracted portion forming an outlet for the sand and air, and suction means connected with the said outlet for drawing a mixture of sand and 65 air into and through the suction device.

3. A boiler flue cleaner provided with a sand and air suction device of approximately U shape comprising upstanding members connected at their lower ends by a bend 70 having a projecting base, one of said members having an air opening adjacent its free end and the other member having a contracted portion, an elongated sand inlet disposed in the bend connecting the members, 75 said inlet lying flush with the upper surface of the projecting base, the contracted member forming an outlet for sand and air, and fluid suction means connected with the said outlet for drawing sand and air in and 80 through the suction device.

In testimony whereof we have signed our names to this specification in the presence of two subscribing witnesses.

ARCHIE RAYMOND URIE.
FREDERICK PHILIP UHRIG.
